UNITED STATES PATENT OFFICE.

DONALD H. YOUNG, OF BERKELEY, CALIFORNIA, ASSIGNOR TO AMERICAN MANGANESE STEEL COMPANY, OF CHICAGO, ILLINOIS, A CORPORATION OF MAINE.

ORE MILL AND GRINDING ELEMENT THEREFOR.

Application filed December 3, 1927. Serial No. 237,347.

This invention relates to mills of the kind in which ore and other materials may be reduced to subdivided form by tumbling or otherwise agitating the materials, usually referred to as "pulp", within a container, in the presence of grinding elements which increase attrition and develop crushing forces within the mass. Heretofore, it has been the practice to introduce into the container of a mill of this kind, rounded stones, balls, tubes, rods and the like. Even cubes have been suggested for use as grinding elements in such mills. But while possessing the desirable feature of flat grinding faces, cubes have the disadvantage of massing together in such a manner as to close up interstitial spaces, and prevent the circulation among them of the material to be ground. Those grinding elements which are of spherical or cylindrical form are fairly efficient as to circulation of material to be ground, but the area of contact between such elements is so small that there is no special tendency to further reduce larger particles in preference to those particles that have already reached the desired degree of fineness.

The object of the present invention is to provide a mill of the kind described, with grinding elements which while favoring free circulation of the pulp during the reduction process, will act more selectively upon the larger pieces and less upon the particles that have reached the desired degree of fineness, and thereby avoid the condition of sliming to a much greater degree than when using grinding elements of design heretofore known; and the invention proceeds upon the principle of constructing grinding elements for use in a mill of the kind described, with substantially plane faces, as distinguished from spheroidal or cylindrical faces and with their said plane faces inclined to their bases and meeting at angles which are very materially less than a right angle, so that the elements are not complementary, and while exercising their superior reduction effect, cannot pack solid and prevent free circulation of the pulp. I have obtained good results by designing the grinding elements in the form of pyramids of polygonal section, and particularly tetrahedrons, or pyramids of triangular section; the base of each pyramid being exposed as one of the grinding faces.

In order that the invention may be fully

understood, an illustrative embodiment thereof is shown in the accompanying drawing, in which—

Figure 1 is a transverse section of a container in the form of a rotary cylinder, into which pieces of ore or other mineral are introduced for the purpose of reduction to subdivided form by the physical process of attrition.

Figure 2 is a perspective view showing the preferred form of grinding element.

Figure 3 is a section in a plane indicated by the line 3^x—3^x of Figure 2.

Figure 4 is a section in a plane indicated by the line 4^x—4^x of Figure 3.

1 represents a rotary cylinder or other tumbling container for mineral substances such as ore (indicated generally at X) and 2 represents grinding elements introduced into and distributed throughout the mass of material X in the cylinder 1 to assist in reducing the material as the latter is tumbled and agitated within the cylinder. Instead of having spheroidal, cylindrical, or even cubical grinding elements as heretofore used or proposed, the grinding elements 2 are designed as polyhedrons, and particularly tetrahedrons or equi-lateral triangular pyramids, as more clearly shown in Figures 2, 3, and 4. Grinding elements constructed on the principle hereinbefore set forth, and used in a tumbling mill, not only present flat grinding faces to the material to be ground, but they are in such a state of instability, when massed with the material to be ground, that they greatly promote, among the elements, the relative movements depended upon for grinding action, and opening up of the interstitial spaces to the entry of the larger particles and causing these to be acted upon in preference to particles that have already attained sufficient degree of reduction.

An important feature of the present invention and one that contributes largely to the instability of the grinding elements above referred to is the absence of parallelism between any two faces of an element.

Grinding elements constructed in the forms of tetrahedrons have the advantage of not packing together and excluding the pulp, since their angles are not complementary in the sense that a space defined by adjacent faces on two grinding elements cannot be filled by a third grinding element. Conse-

quently, there will be free circulation of the material and tumbling of the grinding elements at all times.

In addition to serving with great efficiency when used in a tumbling mill, the grinding element of the present invention lends itself with especial advantage to the production of the elements by the process of casting, since each element constitutes a body having substantially flat grinding faces and having a form that increases in sectional area toward a given face. In the casting of such a geometrical object, with one of its faces presented upwardly, the solidification of the metal progresses proportionally to the sectional area, thereby reducing tendency to form shrinkage cavities and internal shrinkage strains.

I claim:

1. In a tumbling mill, in combination, a container, and grinding elements in said container, each of which is constructed in the form of a polyhedron having faces which are substantially plane and triangular in form, and related one to another at angles materially less than a right angle.

2. In a tumbling mill, in combination, a container, and grinding elements in said container, each of which is constructed in the form of a tetrahedron having faces that are substantially plane and triangular in form.

3. Grinding elements for tumbling mills, comprising polyhedrons each having triangular faces and constructed with a plurality of the angles included between its meeting faces; less than a right angle.

4. Grinding elements for tumbling mills, comprising polyhedrons each having triangular faces and constructed with a majority

of the angles included between its meeting faces, less than a right angle.

5. Grinding elements for tumbling mills, comprising polyhedrons each having triangular faces, and constructed with substantially all of the included angles between its meeting faces less than a right angle.

6. Grinding elements for tumbling mill, comprising bodies in the form of pyramids with triangular sides and having their bases as well as their sides exposed as grinding faces.

7. Grinding elements for tumbling mills, having the shape of tetrahedrons.

8. Grinding elements for tumbling mills, having substantially the shape of regular tetrahedrons.

9. Grinding elements for tumbling mills, having the shape of three-sided pyramids.

10. Grinding elements for tumbling mills, each comprising a polyhedron having substantially all of its adjacent faces at an acute angle to each other.

11. Grinding elements for tumbling mills, provided with acute angular edges and triangular crushing surfaces.

12. Balanced grinding elements for tumbling mills, provided with substantially plane triangular crushing surfaces and interposed acute angular edges.

13. Universally balanced grinding elements for tumbling mills, provided each with similar triangular substantially plane crushing faces disposed at an acute angle each to the others, along their meeting edges.

Signed at Oakland, California, this 7th day of Nov., 1927.

DONALD H. YOUNG.
